UNITED STATES PATENT OFFICE.

GEORGE H. WHEARY, OF RACINE, WISCONSIN, ASSIGNOR TO THE HARTMANN TRUNK COMPANY, OF RACINE, WISCONSIN, A CORPORATION OF WISCONSIN.

TRUNK.

1,093,223.

Specification of Letters Patent. Patented Apr. 14, 1914.

Application filed May 11, 1912. Serial No. 696,549.

To all whom it may concern:

Be it known that I, GEORGE H. WHEARY, a citizen of the United States, and resident of Racine, in the county of Racine and State of Wisconsin, have invented new and useful Improvements in Trunks, of which the following is a description, reference being had to the accompanying drawings, which are a part of this specification.

10 This invention relates to improvements in trunks and more particularly to the means for supporting the garment hangers positioned within the wardrobe compartment of a trunk or any other clothes retainer.

15 It is one of the objects of this invention to provide a trunk in which the garment hangers are supported on fixed tracks having extensible ends which may be swung outwardly, horizontally, from the trunk 20 when the trunk cover is in open position to permit the garment hangers being slid outwardly on said extensible tracks.

A further object of the invention is to provide a trunk having a cover which is 25 locked in closed position by the extensible tracks.

A further object of the invention is to provide a trunk in which the folding portions of the tracks are so constructed as to 30 be self supporting when in open position.

A further object of the invention is to provide extensible garment hanger tracks which are also adapted for use in wardrobe containers or holders other than trunks.

35 With the above and other objects in view, the invention consists of the improved trunk and its parts and combinations, as set forth in the claims, and all equivalents thereof.

In the accompanying drawings in which 40 the same reference characters indicate the same parts in all of the views: Figure 1 is a perspective view of a portion of the improved trunk provided with the garment hanger supporting means, the trunk covers being shown in open position and with the 45 folding portions of the track swung out of the trunk and in horizontal position; Fig. 2 is a front view, on a larger scale, of one-half of a modified form of hanger supporting means shown in closed position, the 50 trunk portion being indicated by dotted lines; Fig. 3 is a top view of the supporting means of the principal form with one of the extensible tracks in partly open 55 position and with portions of the cover locking members in section; Fig. 4 is a front view thereof with the extensible rails in folded position, portions of the trunk being represented by dotted lines; Fig. 5 is a front view, on a larger scale, of the outer 60 ends of the extensible supporting tracks in locked engagement with the trunk cover, the cover being indicated by dotted lines; Fig. 6 is a detail view, on a larger scale, of the inner end of one of the extensible tracks 65 and the cover member engaged thereby; Fig. 7 is a sectional detail view taken on line 7—7 of Fig. 5; Fig. 8 is a detail view of one of the tracks and the cover member engaged thereby; and Fig. 9 is a detail sectional view of one of the tracks.

Referring to the drawings the numeral 12 indicates the wardrobe section of a trunk, 13 the side cover, and 14 the top cover thereof. The upper end of the wardrobe section 75 of the trunk is reinforced by a U-shaped strap 16 which is riveted to the side walls of the trunk and which also serves as a means for attaching the inner ends of the fixed rails 17 thereto. The inner ends of 80 these rails extend through and are riveted to the rear portion of the strap 16 and extend forwardly in a line parallel with the side portions of said strap and their forward end portions are attached to and supported on upwardly extending brackets 18 fastened to the side walls of the trunk. The outer ends of the rails are provided with horizontally extending slots 19 to accommodate the inwardly extending tongues 20 of 85 the extensible rails 21. The tongues extend into the slots 19 and are hinged to the fixed rails 17 by pins 22 to permit said extensible rails to be swung horizontally into longitudinal alignment with the fixed rails or at 90 right angles with relation thereto. The tongues are of sufficient length to extend over the angular hook brackets 23 which are fastened to and depend from the top cover of the trunk. The side edges of the 100 tongues and the hook brackets are beveled off to provide for the tongues easily engaging the hook brackets and to also draw the cover firmly in closed position. The outer ends of the extensible rails are provided with angular fingers 24 which extend inwardly when the extensible tracks are in 105 closed position and are adapted to engage the medially positioned depending cover locking member 25 when the cover is in 110

closed position to lock the extensible tracks against longitudinal movement and thus brace the fixed tracks and the side walls of the compartment against lateral strain.

- 5 The rails are positioned adjacent to the side portions of the trunk and are adapted to support garment hangers 26 removably mounted thereon. These hangers comprise an upper horizontal supporting portion 27, 10 provided with hooked ends 28 which extend over the opposite rails, and a garment hanger portion 29 which depends medially from the horizontal portion and is of suitable shape to support a garment thereon.
- 15 When the top cover is in closed position the angular hook brackets of the cover extend in the path of movement of the hooked ends of the horizontal supporting portion 27 and prevent the garment hangers from 20 accidentally slipping off the ends of the fixed tracks. The shoulders 30 of the extensible tracks engage the outer end portions of the fixed tracks when in open position and serve to prevent the extensible 25 tracks from swinging to positions beyond positions in longitudinal alignment with the fixed tracks.

In the modified form shown in Fig. 2 the rail is shown in connection with a trunk 30 having a closed top and with the angular hook brackets omitted, as it is only desirable to use the medial locking member when used in connection with a trunk of this type.

In use the side cover is opened and the 35 extensible tracks are swung horizontally outwardly to unlock the top cover and the top cover is then opened. The garment hangers may now be slid outwardly on the extensible rails and be separated sufficiently 40 far to permit any hanger to be independently removed or replaced without disturbing the other hangers.

From the foregoing description it will be 45 seen that the trunk is of simple construction and is well adapted for the purpose desired, and that the rails are adapted to support the garment hangers and also lock the upper cover in closed position.

What I claim as my invention is:

- 50 1. A trunk, comprising a compartment provided with a cover having a locking means connected thereto, a fixed garment hanger rail mounted within the compartment, and an extensible rail directly engaging the locking means of the cover and adapted to be swung out of the compartment to disengage the locking means and to longitudinally align with the fixed rail.

60 2. A trunk, comprising a compartment provided with a cover having a locking member connected thereto, a fixed rail mounted within the compartment, and an extensible rail hinged to the outer end of

the fixed rail and directly engaging the locking means of the cover and adapted to be 65 swung horizontally out of the compartment to disengage the locking means and to longitudinally align with the fixed rail.

3. A trunk, comprising a compartment provided with a cover having locking 70 members connected thereto, fixed rails mounted within the compartment, horizontally movable extensible rails hinged to the outer ends of the fixed rails and adapted to swing horizontally out of the compartment, 75 said extension rails adapted to engage the locking members of the cover and lock said cover in closed position when swung into the compartment.

4. A trunk, comprising a compartment 80 having a cover, a fixed rail mounted within the compartment, and a horizontally movable extensible rail hinged to the outer end of the fixed rail and engaging the cover and adapted to swing horizontally out of the 85 compartment and free from engagement with the cover and to a position in longitudinal alignment with the fixed rail and to be held in extended position thereby.

5. A trunk, comprising a compartment 90 having a cover provided with a medial locking member, fixed rails mounted within the compartment, and extensible rails hinged to the outer ends of the fixed rails and having angular fingers projecting from their free 95 ends which engage the locking member of the cover when swung horizontally into the compartment.

6. A trunk, comprising a compartment having a cover provided with locking members, fixed tracks mounted within the compartment, extensible tracks hinged to the outer ends of the fixed tracks and having tongues provided on their inner ends which engage the locking members of the cover 105 when said extensible rails are swung horizontally into the compartment.

7. A trunk, comprising a compartment having a cover provided with a medial locking means and with angular locking members 110 fixed rails mounted within the compartment, and extensible rails hinged to the outer ends of the fixed rails and adapted to be swung horizontally into the compartment, said extensible rails provided with 115 tongues on their inner ends which engage the angular locking members and with angular locking fingers on their free ends which engage the medial locking member.

In testimony whereof, I affix my signature, in presence of two witnesses.

GEORGE H. WHEARY
